UNITED STATES PATENT OFFICE.

CHARLES P. KNAPP, OF DEPOSIT, NEW YORK.

CARPET STRETCHER AND TACKER.

SPECIFICATION forming part of Letters Patent No. 651,253, dated June 5, 1900.

Application filed February 12, 1900. Serial No. 4,947. (No model.)

To all whom it may concern:

Be it known that I, CHARLES P. KNAPP, of Deposit, in the county of Delaware and State of New York, have invented a new and useful Improvement in Carpet Stretchers and Tackers, of which the following is a specification.

My invention is an improvement in devices for stretching and tacking carpet, and particularly the device shown and described in Patent No. 627,428, granted to me June 20, 1899; and it has for its object an apparatus of this character which will be convenient to handle and of efficient operation and which will be of comparatively few parts and of simple construction.

The invention consists in certain details of construction, which I shall hereinafter specifically describe, and then point out in the appended claims.

Reference is to be had to the accompanying drawings, forming part of this specification, in which like characters of reference indicate corresponding parts in all the views.

Figure 1 is a perspective view of my improved carpet stretcher and tacker. Fig. 2 is a longitudinal section of the same. Fig. 3 is an inverted plan view with the stretcher-plate in reversed position. Fig. 4 is a plan view of the stretcher-plate detached. Fig. 5 is a detail plan view of the tack-holding jaws. Fig. 6 is a detail perspective view of the tack-holding jaws shown detached, and Fig. 7 a detail cross-section on the line 7 7 of Fig. 2.

The head 10 of my device is made, preferably, of malleable iron and is provided with stub-axes 11, on which rubber-tired wheels 12 are journaled. Two arms 13 extend upwardly and rearwardly from the head and receive between them the lower end of the handle-rod 14, said rod being formed with an approximately-rectangular portion 14^a, whose upper and lower surfaces are longitudinally grooved to receive, respectively, the tack chute or tube 15 and the hammer-operating rod 16. The latter is pivoted at its rear end to a hand-lever 17, fulcrumed to move in a vertical plane in the handle-rod and extending above the upper surface of the same, and at the other end the hammer-operating rod 16

is bent as shown at 18 and enters one of the openings in the hammer 19. The said hammer, as shown particularly in Fig. 2, has a curved lower end pivoted on a lug 10^a on the head 10 and working snugly in a recess 10^b in one of the axles 11, whereby it is prevented from wabbling, and it is formed at the free end of its shank with a weighted or heavy head 19^a, from which projects a driving-finger 19^b, the said finger being so arranged at 60 an angle to its head and with respect to the pivotal point of the hammer that it will extend exactly in a vertical plane when it is driving a tack, thereby giving a direct downward stroke. It should be noted in this connection, referring especially to Fig. 2, that by constructing the hammer-arm with a rearwardly-curved lower pivotal end and having the weighted head at the opposite end of this arm the head will lie back of the pivotal point 70 even when the arm lies mainly in a vertical plane, and while it thereby readily maintains itself in upper position it can by a slight pull on the operating-rod 16 be easily thrown down to drive the tack.

Extending forwardly from the head 10 are spaced-apart supporting-arms 20, which are formed at their front ends with bearing-sockets 20^a, in which are hung the tack-holding jaws 21, said jaws being swung from eccentric pintles 21^a, directly in line with the driving-finger 19^b, so that after a tack has been dropped point downward into the chute or tube 15 and has been directed into the jaws by the upward extension 21^b of one jaw at the 85 discharge end of the chute a reciprocation of the hand-lever 17 will cause finger 19^b to drive the tack out of the jaws into the carpet and floor. The jaws 21 are normally held with their lower ends shut, so that they may prevent the tack from dropping therefrom before the desired time, and for this purpose a U-shaped spring 22 is fitted in a correspondingly-shaped groove 22^a, formed in a web 23, connecting the supporting-arms 20 near their 90 front ends. The ends of the spring extend forwardly along the sides of the lug 23^a (which supports the lower end of the chute 15) to an engagement with the upper surfaces of lugs 24 on the jaws, and as these lugs extend in 100

a horizontal plane on each side of the pintles 21^a it is evident that the downward pressure of the spring tends to keep the jaws closed. The spring is held in place by the overlapping head of a bolt 25, which extends through the web 23. 26 designates a stop cast on the side of one of the arms 13 and adapted to limit the backward movement of the hammer.

27 designates a tack-receptacle pivoted to 10 the under side of the handle-rod in convenient proximity to the mouth of the chute 15 and held in closed position by a suitable spring-catch 27^a.

In order to stretch the carpet and hold it 15 stretched while it is being tacked, I employ a stretching-plate 28 of triangular shape and formed with a central clamping-block 29, adapted to fit against the under side of the web 23, being held rigidly in place by the 20 thumb-nut 29^a, working on the bolt 25, inserted through the clamping-block. My improved stretcher 28 is designed to be interchangeable. For instance, as illustrated in Fig. 1, it may be held with the end *a* located directly 25 in front of the tack-holding jaws, the diverging adjacent sides *b* being provided with forwardly-turned prongs 30. When in this position, it enables the device to be easily used in the corners of rooms and other close places, 30 allowing the tacks to be driven close to the corners of the carpet, and also enables the operator by lateral manipulations of the handle-rod to stretch the carpet both forwardly and laterally, or when it is desired to stretch 35 one edge of a carpet when the adjacent sides are already tacked and to get a broad bearing-surface the plate is turned around and clamped in the position illustrated in Fig. 3, when the straight side *c* extends equally on 40 each side of the tack-holding jaws and slightly in front of the same, the said side being also provided with prongs 31, which are turned forwardly in an opposite direction to the prongs 30 and which terminate in a slightly- 45 higher plane than the prongs 30, so that they will in no wise interfere with the action of the latter when the stretcher is held in the position illustrated in Fig. 1.

As shown in detail in Fig. 7, the thumb-nut 29^a is provided with wings 29^b, which are somewhat sharpened and bent to form prongs which act in conjunction with the prongs 30 and assist the tacker by taking hold of the carpet.

55 In practical operation the handle-rod is elevated, causing the foremost prongs on the stretcher to take hold of the carpet. The handle-rod is then depressed and the forward end of the stretcher raised, the wheels acting as 60 a fulcrum, until every prong on the angular sides of the plate and on the thumb-nut engages the carpet, and the device is then pushed forwardly with the edge of the carpet out of contact with the floor, thereby doing away 65 with the friction which would otherwise occur. When the carpet is sufficiently stretched,

the handle-rod is again elevated and held tightly between the side and one arm of the operator, while one hand picks a tack out of the receptacle and places it point down into the mouth of the chute 15, whence it falls to the jaws and is caught therein, with its shank projecting out of the same. The hammer is then operated by means of the hand-lever 17 and the tack driven out of the jaws into the 75 carpet.

I wish it understood that the wheels illustrated serve mainly as a fulcrum, as just described, and that I may use any other suitable device for this purpose.

Having thus described my invention, what I claim as new, and desire to secure by Letters Patent, is—

1. In a device of the character described, a handle-rod, a head to which the rod is connected, said head having supporting-arms extending beyond the rod in a forward direction and formed with bearing-sockets, tack-holding jaws having eccentric pintles fitted loosely in said sockets and having lugs extending on each side of said pintles, a spring bearing downwardly upon said lugs whereby to hold the jaws normally closed, and means for driving a tack out of said jaws, as set forth.

2. In a device of the character described, a handle-rod, a tack-chute mounted thereon, tack-holding jaws located at the discharge end of said chute and swung on pintles, said jaws being provided with lateral lugs extending oppositely therefrom on each side of said pintles, and a spring bearing downwardly on said lugs whereby to close the jaws, as set forth.

3. In a device of the character described, the combination with the head, of the supporting-arms extending forwardly therefrom, and formed with bearing-sockets and a grooved web in the rear of said sockets, tack-holding jaws having pintles whereby they are mounted to swing in said sockets, said jaws being formed with lugs extending on each side of said pintles, and a U-shaped spring held in the groove of the web and having free ends pressing downwardly on said lugs, as set forth.

4. In a device of the character described, the combination with a supporting member having a bolt thereon, of a stretching-plate arranged for connection to said bolt and formed with prongs, and a thumb-nut for holding said plate and having prongs arranged to act in conjunction with the prongs on the plate, as set forth.

5. In a device of the character described, a 125 stretcher-plate of triangular shape formed on two of its sides with prongs bent in one direction, and also formed on its third side with prongs bent in the opposite direction and whose points terminate in a slightly-higher 130 plane than the first-named prongs, as set forth.

6. In a device of the character described
the combination with a supporting member
formed with a web, of a triangular stretching-
plate provided with a bearing-block adapted
5 to fit the said web, and a detachable fasten-
ing for securing the block and web together,
as set forth.

In testimony whereof I have signed my
name to this specification in the presence of
two subscribing witnesses.

CHAS. P. KNAPP.
